W. J. KNOX.

RAILWAY CAR SIDE DOOR FRAME.

APPLICATION FILED MAY 6, 1912.

1,079,652.

Patented Nov. 25, 1913.

UNITED STATES PATENT OFFICE.

WILLIAM J. KNOX, OF DUBOIS, PENNSYLVANIA, ASSIGNOR TO COMMONWEALTH STEEL COMPANY, OF ST. LOUIS, MISSOURI, A CORPORATION OF NEW JERSEY.

RAILWAY-CAR SIDE-DOOR FRAME.

1,079,652.

Specification of Letters Patent.

Patented Nov. 25, 1913.

Application filed May 6, 1912. Serial No. 695,483.

To all whom it may concern:

Be it known that I, WILLIAM J. KNOX, a citizen of the United States, residing at Dubois, Pennsylvania, have invented a certain new and useful Improvement in Railway-Car Side-Door Frames, of which the following is a full, clear, and exact description, such as will enable others skilled in the art to which it appertains to make and 5 use the same, reference being had to the accompanying drawings, forming part of this specification, in which—

Figure 1 is an elevational view of a side door frame of my improved construction. 15 Fig. 2 is an enlarged vertical section taken approximately on the line 2—2 of Fig. 1. Fig. 3 is an enlarged detail section taken approximately on the line 3—3 of Fig. 1. Fig. 4 is a detail section taken approximately 20 on the line 4—4 of Fig. 1. Fig. 5 is an elevational view of the lower portion of the form of door frame utilized on cars having continuous side sills. Fig. 6 is a horizontal section taken approximately on 25 the line 6—6 of Fig. 5. Fig. 7 is an enlarged detail section taken approximately on the line 7—7 of Fig. 5.

This invention relates generally to railway cars, and more particularly to a panel 30 or side door frame comprising a pair of door posts and top and bottom rails, all of which parts are formed integral and are adapted to be readily combined with the side sills and side plates of a car body frame 35 to form a very strong and rigid construction that will be particularly effective in resisting service strains and stresses.

In cars having continuous side sills extending from the floor level to the window 40 sills, the greater portion of the load is carried by said sills, but in cars having large side door openings such as baggage, express and mail cars, the door opening extends to the floor level or thereabout, thereby materially 45 reducing the depth of the side sills, and where cars are thus constructed, it is necessary that the side sills be made very much heavier in the locality of the door openings in order to proportionately distribute the 50 load-carrying strength of the side sills.

The principal object of my invention is to provide a one-piece cast metal frame comprising a pair of posts and top and bottom rails that are adapted to engage the top and 55 bottom chords of the car side frame, and

which rails perform the function of reinforcing members to bridge the space above and below the wide door opening necessary in the sides of cars particularly utilized as baggage, express and mail cars.

60

To the above purposes my invention consists in certain novel features of construction and arrangement of parts hereinafter more fully described and claimed.

As shown in the accompanying drawings, 65 my improved door frame comprises a pair of vertically disposed upright members 1 that form door posts, the same being preferably channel-shaped in cross section, and formed integral with and connecting the 70 lower portions of these posts is a channel-shaped rail 2, the top plate of which is preferably inclined to form a threshold plate 3 for the door frame. This lower rail 2 is provided at its ends with integral extensions 2^a that project beyond the lower ends of the posts 1, which extensions provide means for attaching the corresponding ends of the sections of the side sills, as shown by dotted lines in Fig. 4. Formed integral 75 with the upper ends of the posts 1 is a channel-shaped top rail 4 that forms a lintel for the door frame, and the ends of this rail project beyond the posts 1, as designated by 4^a.

The top plate A of the car frame, which is usually a continuous flanged member, lies immediately above and is rigidly fixed to the rail 4 and its extensions 4^a, and where the door frame is constructed for use in connection with side frames having top plates that are Z-shaped in cross-section, the outer 80 face of the rail 4 is slightly recessed, as designated by 4^b in order to accommodate the depending outer flange of said side plate. 90

Integral strengthening webs 4^a are formed on the interior of the top rail 4, and corresponding strengthening ribs 2^b are formed within the bottom rail 2.

The form of the frame illustrated in Figs. 1 to 4 inclusive is designed particularly for use in connection with side sill members of an underframe that are made in sections, and where such construction is carried out, the central portion of the rail 2 is made comparatively heavy in order to provide the requisite strength between the adjacent ends of the sections of the sections of the side sill. The extensions 2^a in this form of the frame are slightly offset relative to the front and 100 105 110

bottom faces of the central portion of the rail 2 in order to accommodate the flanges of the side sills.

In the form of frame utilized in connection with continuous side sills the bottom rail 2 can be made comparatively light in weight, and the lower portion of the outer face of said rail is recessed, as shown in Fig. 7 in order to accommodate the vertically disposed flange of the side sill.

A side door frame of my improved construction is comparatively simple, can be easily and cheaply manufactured, and being formed in a single piece, can be readily combined with and connected to the side sills and top plates of a car body frame with comparatively little labor and expense.

The frame provides a strong, rigid panel for the side of a car frame, and the continuous top and bottom rails combine with the side sills and top plates of the car frame to form a particularly strong construction above and below the wide door opening.

It will be readily understood that minor changes in the size, form and construction of the various parts of my improved side door frame can be made and substituted for those herein shown and described without departing from the spirit of my invention, the scope of which is set forth in the appended claims.

I claim:

1. The combination with a railway car side frame top and bottom chords, of a car door frame cast in a single piece, comprising vertically disposed channel-shaped members which perform the functions of door posts, lateral extensions at the ends of said upright members for attachment to the upper and lower chords of the car side frame, a horizontal channel-shaped member between the upper ends of said upright members, which horizontal member performs the function of a door frame lintel, and a horizontal channel-shaped member between the lower ends of the upright members, the top flange of which last mentioned channel-shaped member extends inwardly a substantial distance to form a threshold plate for the door frame.

2. The combination with a railway car side frame top and bottom chords, of a car

door frame cast in a single piece and comprising vertically disposed channel-shaped members which perform the functions of door posts, lateral extensions at the ends of said upright members for attachment to the upper and lower chords of the car side frame, a horizontal channel-shaped member between the upper ends of said upright members, which horizontal member performs the function of a door frame lintel, a horizontal channel-shaped member between the lower ends of the upright members, which last mentioned member performs the function of a door sill, and a threshold plate integral with and extending rearwardly from the last mentioned horizontally disposed member.

3. As a new article of manufacture a car side door frame, comprising a pair of substantially channel-shaped posts, a substantially channel-shaped rail between the upper ends of said posts, extensions on the ends of said rail for attachment to the side plate of a car side frame, a substantially channel-shaped rail between the lower portions of the posts, an inwardly projecting threshold plate on the upper portion of said last mentioned rail, extensions at the ends of said last mentioned rail for attachment to the side sill of the car frame, all of which parts are cast integral.

4. The herein described car side door frame cast in a single piece, and comprising a pair of substantially hollow door posts, a substantially hollow lintel between the upper ends of said door posts, extensions at the ends of the lintel for attachment to the car frame side plate, a substantially hollow sill member between the lower ends of the posts, a threshold plate integral with said sill, and extensions at the ends of said sill member for attachment to the side sill of the car body frame, which last mentioned extensions are off-set with respect to the main body portion of the sill member.

In testimony whereof I hereunto affix my signature in the presence of two witnesses, this 27th day of April, 1912.

WM. J. KNOX.

Witnesses:

HAL C. BELLVILLE,
FRED W. DIECKMANN.
